his ATTORNEY

UNITED STATES PATENT OFFICE.

BENJAMIN F. DU BOIS, OF NEW YORK, N. Y.

UMBRELLA OR CANE HEAD.

SPECIFICATION forming part of Letters Patent No. 368,077, dated August 9, 1887.

Application filed September 18, 1886. Serial No. 213,941. (No model.)

To all whom it may concern:

Be it known that I, BENJAMIN F. DU BOIS, a citizen of the United States of America, and a resident of New York city, in the county 5 and State of New York, have invented certain new and useful Improvements in Receptacle-Chambers in the Heads of Umbrella Sticks or Canes, of which the following is a specification.

10 This invention consists in providing in the head of an umbrella stick or cane a chamber, (suitable for the reception and safe keeping of small articles, such as coin, car-tickets, &c.,) which is formed of two parts, the one adapted to swivel on the other in a plane at right angles to the axis of the stick, substantially as will be hereinafter described.

15 The invention also consists in providing in the head of an umbrella stick or cane a chamber formed of two parts, one of which is adapted to swivel on the other in a plane at right angles to the axis of the stick, and when such parts are closed to be secured in such position, all substantially as hereinafter described; and it further consists in providing in the head of an umbrella stick or cane a chamber formed of two parts, one of which is adapted to swivel on the other in a plane at right angles to the axis of the stick, and one 25 of the chamber-forming parts provided with a pivoted clasp having ears or projections which engage with grooves in the said parts, substantially as hereinafter described and shown, reference being had to the accompanying drawings, in which—

20 Figure 1 is a side view of an umbrella having the handle-stick thereof provided with the receptacle of this invention. Fig. 2 is a view on a larger scale of the side of the handle-receptacle. Fig. 3 is a vertical section on line 3 3, Fig. 2. Fig. 4 is a plan view of the lower part of the handle-receptacle on a plane indicated by line 4 4, Fig. 2. Figs. 5 and 6 are views of modifications to be hereinafter referred to.

25 In the drawings, A represents the stick of an umbrella having at its end a knob or handle, B. This knob or handle B is made with an interior chamber, C, which chamber is adapted to be opened and closed by a lid or cover, D, which may form part of the knob B. As shown in Figs. 1, 2, and 3, the knob B is

made in two hemispherical parts, each hollowed or chambered interiorly, and each part provided with a web, b b', extending from the 55 edge or circumference toward the center for a short distance, in one of which webs is a stud, d, and in the other a socket, f, which stud and socket fit the one within the other and allow a swivel or turning of the cover part D in a 60 plane at right angles to the axis of the stick A upon the part F of the parts forming the knob or handle. Each of the parts F D is provided with a groove, g, or other form of depression or shoulder, and to one or the other 65 of the parts a clasp, G, is hinged or pivoted, as at h, which clasp has one or more ears or extensions, k, which are in the same axial plane as the grooves g, and when the clasp is closed the ears k project into the grooves g and prevent the turning or swivel of the cover part 70 D upon the other, F, to open the receptacle-chamber. The face of the clasp is of a corresponding arc shape to the circumferential curvature of the parts F D, so as to lie, when 75 closed, snugly against same and to present no appreciable extension from the general contour of the handle or knob formed by such parts.

The hemispherical chambered parts F D, forming the knob or handle, are preferably 80 made of metal, and can be "struck up" in the usual way of forming metallic shells of similar shape, and the part F is provided with a tubular extension, H, into which the stick fits, and is secured with any suitable fastening 85 device or means, and the interior of these chambered parts F D is lined with a layer or thickness, m, of finishing and ornamental material, such as velvet or plush, enamel, cement, or other desirable material or substance. 90

While it is preferable and most practical to form the knob B of two hemispherical parts, F D, and each chambered as shown, each of such parts may be exteriorly hemispherical, or more or less approaching that shape, and 95 only one of them chambered, the other being solid, or only one, and either one, may be hemispherical and chambered, as seen in Figs. 5 and 6, and where it is the outer one, D, as shown in Fig. 6, the umbrella should be held 100 with handle end downward in swinging the said part D open—first releasing the clasp therefor—to prevent the articles in the receptacle from falling from the chamber C before

being picked therefrom by the person holding the umbrella or cane.

In Fig. 5 a series of partitions, *n*, are shown in the chamber of the handle-knob in which coins or other articles may be placed and held from rattling, and in Fig. 6 a spring, *p*, is shown, which would serve a similar purpose, and also would prevent the articles from falling out on an opening of the chamber-lid or part *D*. Other manners of adaptation of the parts for being opened and closed and secured closed than herein described may be employed, such as a hinge-joint to the lid of the chambered knob similar to a watch-case cap-hinge, and also other forms of clasp or catch may be used than that shown; but the manner described of swiveling and of fastening the parts is simple, cheap, practical, and satisfactory. The lining of the interior with a finishing material allows the use of an inferior metal, such as brass or copper, the corrosion of which will have no effect on the interior, while the exterior may be nickel, silver, or gold plated, as desired, as also can be the interior.

The convenience of such a receptacle on an umbrella or walking-stick is evident, especially at such times as a person has on gloves and it is inconvenient to put his hand in his pocket for coin, car-tickets, &c.

Having thus described my invention, what

I claim, and desire to secure by Letters Patent, is—

1. An umbrella stick or cane having a knob or chamber at its handle end formed of parts *F* *D*, the one adapted to swivel on the other in a plane at right angles to the axis of the stick, substantially as described.
2. An umbrella stick or cane having a knob or chamber at its handle end formed of parts *F* *D*, the one adapted to swivel on the other in a plane at right angles to the axis of the stick and when closed to be secured in such position, substantially as described.
3. An umbrella stick or cane having a knob or chamber at its handle end formed of parts *F* *D*, the one adapted to swivel on the other in a plane at right angles to the axis of the stick, one of said parts *F* *D* being provided with a pivoted clasp, *G*, having ears *k*, which engage with grooves *g* in the said parts, substantially as described.

In testimony that I claim the foregoing as my invention I have signed my name, in presence of two witnesses, this 16th day of August, 1886.

BENJM. F. DU BOIS.
